UNITED STATES PATENT OFFICE.

XENOPHON CAVERNO AND WILLIAM E. FOWLER, OF DENVER, COLORADO.

RAILWAY FREIGHT-CAR.

SPECIFICATION forming part of Letters Patent No. 498,234, dated May 30, 1893.

Application filed June 24, 1892. Serial No. 437,878. (No model.)

To all whom it may concern:

Be it known that we, XENOPHON CAVERNO and WILLIAM E. FOWLER, citizens of the United States, residing in Denver, in the 5 county of Arapahoe and State of Colorado, have invented a new and useful Improvement in Railway Freight-Cars, of which the following is a specification.

Our invention relates to an improvement 10 in railway freight cars of the type known as coal cars; and the object of our improvement is to bind together the opposite coal sides, automatically, at or near their upper edges, when the end-gate is raised to position to retain the load, so that the coal sides cannot 15 be sprung outward by the pressure of the load against them. We attain this object by the mechanism illustrated in the accompanying drawings, in which—

20 Figure 1 is a vertical cross section of a coal car body; Fig. 2 a plan of one end of a coal car body; Fig. 3 a side elevation of one end of a coal car body with the nearest coal side removed. Fig. 4 is a detail of the upper left 25 hand corner of Fig. 1; and Fig. 5 a plan of Fig. 4. The hinged end-gate is shown in a vertical position, or "position to retain the load," in Figs. 1, 2, 4, and 5. In Fig. 3 it is shown swung downward and resting on the 30 floor.

Similar letters refer to similar parts throughout the several views.

The ordinary construction of this type of car is as follows: The coal sides or side boards 35 C. C.' are bolted to the standards E E'. The lower ends of the standards are extended downward over the side sills and are fastened to the side sills by means of "U" bolts or otherwise. The end-gate A is hinged to the 40 floor by means of eye bolts passing through it and engaging with eye bolts passing through the sills and floor. When the car is loaded with lumber, or similar material, the end-gate lies on the floor, as in Fig. 3, and is covered 45 by the load. When the car is to be loaded with coal, or similar material, the end-gate is raised to an upright position where it rests against the cleats D D', attached to the coal sides. It will be seen that the coal sides are 50 held in an upright position simply by the lower ends of the standards being fastened to the side sill. The leverage being so short com-

pared with the leverage of the load the coal sides soon sag outward and unless watched very carefully and the "U" bolts continually 55 tightened they break off altogether. This is the one great objection to this class of cars.

Our improvement is as follows: A metal strap or rod M is bolted to the inner face of the end-gate near its upper edge; each end 60 of this strap or rod is turned backward forming the hooks N N', which extend back across the end of the end-gate, the upper corners of the end-gate being cut away to receive them. To each coal side, opposite the end of the end- 65 gate when it is resting against the cleat, is fastened the metal strap or loop K K'. These straps extend up the outer face of the coal side; are turned at right angles over the upper edge of the coal sides and extend inward 70 so far that, when they are turned down, the hook or loop, so formed, shall engage with the hooks N. N', when the end-gate is raised. The straps K K' are returned below this loop 75 and bolted to the inner face of the coal side— the bolt passing through the part of the strap on the outer face. The upper corners of the end-gate are cut away to clear this loop so that the end-gate rests against the cleats, as before. When the end-gate is raised the 80 hooks N N' engage, automatically, with the loops K K', thus binding the opposite coal sides together, so that they cannot be sprung outward by the pressure of the load. When 85 the end-gate is lowered the hooks readily disengage the slight taper given them, and the offset to the loops, facilitating this as well as the engagement when the end-gate is raised. The action is entirely automatic, no more attention being required than where the improvement is not used. The strap M, being subjected merely to a tensile stress, need not 90 be as heavy as the hooks N N'. The form shown in the drawings, in which the strap is doubled on itself, at each end, the hooks being formed of this double part, gives this result very effectively and simply.

We would here call attention to the fact that our device is a tie for the coal sides and not in any sense a lock for the end-gate; that 100 it is especially designed for use with inward swinging end-gates where no device is needed to fasten up the end-gate, the load itself performing that function; that the motion of the

end-gate is in no way impeded by it. We would explain that the word "coal-cars," as used in this specification, refers to a type of cars and does not refer to class of service or character 5 of load; that the word "coal-side" is synonymous with "side board," and is likewise independent of class of service or character of load.

We are aware that previous to our invention, cars of this type have been constructed having a loose hook attached to the coal side to be slipped by hand into an eye on the end-gate, after the end-gate is raised to the cleat, thus binding together the opposite coal sides; 15 but we are not aware of any device, for this purpose, which acts automatically or forms a continuous metallic tie between the coal sides.

We are aware that devices have been used on the outward swinging end-gates of road 20 wagons which tie the side boards together automatically when the end-gate is raised, but we are not aware that any such device has ever been invented which is so formed and placed as to be effective when applied to inward swinging end-gates.

We therefore do not claim the method of binding together the coal sides automatically by means of a device attached to the hinged end-gate except, first, when a continuous metallic tie is formed between the coal sides, or 30 second, when the device is so formed and placed as to be effective in combination with an inward swinging end-gate.

What we do claim as our invention, and 35 desire to secure by Letters Patent, is—

1. In railway freight cars, having coal-sides and inward swinging end-gates, a loop or hook on the inner face of each coal side, in combination with a suitable device on the inward swinging end-gate with which each of said loops or hooks engages automatically when the end-gate is raised, thus binding the opposite coal sides together. 40

2. In railway freight cars having coal sides and inward swinging end-gates the metal 45 hooks N and N' the outer end of each lying between the end of the end gate and the adjacent coal side, in combination with the loops K and K' or some other suitable device on the inner face of the coal side with which they engage automatically, when the end-gate is raised, thus binding the opposite coal sides together. 50

3. In railway freight cars having coal-sides and inward swinging end-gates, a metal rod or strap attached to the end-gate, each of its ends being formed into or attached to a metal hook or loop, which engages with a suitable device on the inner face of the adjacent coal-side, when the end-gate is raised, thus binding together the opposite coal-sides so that they can- 55 not be sprung outward by the pressure of the load against them; the tie rod and not the end-gate itself being in tension when the load presses against the coal sides. 60
